US0D1102817S

(12) **United States Design Patent** (10) **Patent No.:** **US D1,102,817 S**
(45) **Date of Patent:** **** Nov. 25, 2025**

(54) **BOTTLE LID**

(71) Applicant: **EVERICH AND TOMIC
HOUSEWARES CO., LTD.**, ZheJiang
(CN)

(72) Inventor: **Huajun Yao**, ZheJiang (CN)

(73) Assignee: **EVERICH AND TOMIC
HOUSEWARES CO., LTD.**, Hangzhou
(CN)

(**) Term: **15 Years**

(21) Appl. No.: **29/930,399**

(22) Filed: **Feb. 29, 2024**

(30) **Foreign Application Priority Data**

Aug. 29, 2023 (CN) 202330556150.0
